Primary Examiner — Ruth McInroy*(74) Attorney, Agent, or Firm* — Michael Best & Friedrich LLP(57) **CLAIM**

We claim the ornamental design for a handheld vacuum cleaner, as shown and described.

DESCRIPTION

FIG. 1 is a perspective view of a handheld vacuum cleaner showing our new design;

FIG. 2 is a right side view of the handheld vacuum cleaner shown in FIG. 1.

FIG. 3 is a left side view of the handheld vacuum cleaner shown in FIG. 1.

FIG. 4 is a front side view of the handheld vacuum cleaner shown in FIG. 1.

FIG. 5 is a back side view of the handheld vacuum cleaner shown in FIG. 1.

FIG. 6 is a top side view of the handheld vacuum cleaner shown in FIG. 1; and,

FIG. 7 is a bottom side view of the handheld vacuum cleaner shown in FIG. 1.

The elements shown in broken lines form no part of the claimed design.

1 Claim, 6 Drawing Sheets# US D840,615 S
